UNITED STATES PATENT OFFICE.

WILLIAM H. JACOBY, OF MINNEAPOLIS, MINNESOTA.

RAILWAY-CAR.

SPECIFICATION forming part of Letters Patent No. 439,404, dated October 28, 1890.

Application filed March 5, 1888. Serial No. 266,202. (No model.)

To all whom it may concern:

Be it known that I, WILLIAM H. JACOBY, of Minneapolis, in the county of Hennepin and State of Minnesota, have invented certain new 5 and useful Improvements in Railway-Cars, of which the following is a specification.

My invention relates to improvements in the running-gear of railway-cars, and the object I have in view is to provide a car that 10 may be caused to turn in either direction onto a branch or side track without the use of movable switches, or may be caused to pass the switches and follow the straight track, as desired.

15 Other objects of the invention will appear from the following detailed description, taken in connection with the accompanying drawings, in which—

Figure 1 is a side elevation of a portion of 20 a street-car embodying my invention. Fig. 2 is a longitudinal section of the same. Fig. 3 is a bottom view. Fig. 4 is a horizontal section through the center of the wheels and journals. Fig. 5 is a partial bottom view 25 showing the mode of changing the angle of the wheels. Figs. 6 and 7 are details of the journal-box. Fig. 8 is a section of track, showing the curves and the manner of constructing the switches. Fig. 9 is a section of track, 30 showing a curve and the portion taken by a car in passing said curve. Fig. 10 is a detail.

In the drawings, 2 represents the body of the car supported upon a truck-frame 4. This truck-frame may be of any suitable construction, 35 preferably formed with the outer longitudinal bars 6 and the central longitudinal bar 7, which are properly braced or framed together, and to this frame the running-gear of the car is attached.

40 The wheels 8 which carry the car may be of ordinary construction and are mounted upon axles 10. I prefer to construct these axles as shown in Fig. 4, providing a separate axle for each wheel, extending from the journal-box 12, located outside the wheel upon the bar 6, to the journal - box 13, located at the inner extremity of the axle under the central bar 7. This box is preferably secured to the housing 15 by the pivots 16, centrally located at the top and bottom of the said box. The outer box 12 is also pivoted in a similar

manner between the supporting-plate 17 and the strap 18, secured to the outer bars of the frame. The housing 15 is supported in ways 19 upon the central bar 7 of the frame, and 55 are arranged to slide longitudinally of the frame. A series of friction-rolls 21 may be placed between the housing and the way, in order to allow it to move more freely.

20 represents a barrel or sheave held in 60 bearings on the truck-frame. A chain or cable 22 passes around this sheave and is secured to the housings 15. A sprocket-wheel 24 is mounted upon the shaft 25, which is held in bearings preferably upon the body of 65 the car, extends upward above the platform of said car, and is provided with a handle or lever 26, by which it is operated. A chain 27 is passed over the sprocket 24 and is connected to the housings 15. A turn-buckle 28 70 may be placed in the line of the chain between the sprocket and the housing to take up the slack in the chain. The chain or cable 22, passing around the barrel 20 and attached to the sliding housing 15 on one side, and the 75 chain 27, passing around the sprocket 24 and attached to the housing on the opposite side, form a means for longitudinally moving the housings and journal-boxes pivoted therein. As the sprocket is partially revolved, the 80 housing upon one side is thrown forward and the housing upon the other side is drawn backward, moving the inner end of the axle and throwing the wheels upon an angle either to the right or left, as the case may be. 85

I do not confine myself to the manner described of moving the housing and boxes, as other means may be employed for doing this without departing from my invention, and both boxes may be moved at the same time, 90 or one only may be moved. This axle, as described, may be applied to one or both ends of the car, and when applied to both ends one may be locked straight while the other is being operated. A flange or collar 30 is preferably formed upon the inner end of the axle, and as the housing 15 is moved the boxes 12 and 13 will turn on their pivots and allow for the angularity of the said axle. The collar 30, bearing upon the inside of the journal-box, will hold the axle against this box 100 and draw the wheel toward the center, mak-

ing the distance between the flanges shorter when the wheels are on the angles. The inner rail of the curve may be made continuous, but on the outer rails, or wherever the flanges of the wheels pass, it is necessary to leave an opening to allow therefor.

I have shown in Fig. 8 a view of the track which may be used with my improved car, and have represented a straight track and curves starting from the straight track at the same point and running both ways therefrom. In this view 1 1 represent the rails of the straight track, 3 3 represent the rails of the curve in one direction, and 5 5 represent the rails of the opposite curve. It will be understood that the car may be used on a track having one or more curves. The inner rail 3 of the curve is preferably continuous, and the inner rail of the opposite curve 5 is also preferably continuous. The outer rails of the curves 3 and 5, as well as of the straight track 1, are brought together, as shown in Fig. 8, in such a manner as to carry out the lines of their respective tracks, but to allow space at their juncture for the flanges of the wheels in following either of the lines to pass the other without obstruction.

The operation is as follows: When the axles are locked in line with each other, as shown in Figs. 3 and 4, the wheels will be in the same relative position as in a car of ordinary construction, and as long as they are held in this position they will follow the straight track or the rails denoted by 1 1 in Fig. 8. The flanges will pass through the openings between the rails 1 and 5 on one side, and 1 and 3 upon the other, as denoted by dotted lines in Fig. 8, and the car will hold to the straight track. If it should be required to cause the car to follow one of the curves, the lever 26 at the forward end of the car is operated and the axles are thrown upon an angle, as shown in Fig. 5 and in dotted lines in Fig. 8. This causes the wheel-flange to hug and follow the inner rail 3 of the curve and draw the opposite wheel away from the outer rail. The distance between the flanges being shortened by the angularity of the axle, the flange on the outer rail will be drawn toward the center sufficiently to insure its passing the opening or division between the rails and following the line of the curved outer rail. The angularity of the axle re-

lieves the friction between the wheel and rail, as the line of the axle will be radial to the curve. Each wheel being supported upon a separate axle allows the outer wheel to travel faster than the inner one in passing a curve and thus causes less resistance. It will be seen that it is only necessary in passing into a curve to angle or change the line of the forward wheels, as this will lead the car into the curve, and the back axle and wheels will be drawn over sufficiently to follow the line of the curve.

I claim as my invention—

1. The combination, with a railway-car, of supporting-wheels each mounted upon an independent axle, pivoted boxes supporting the outer ends of said axles and permitting said axles to have a longitudinal movement in said boxes, longitudinally-movable housings supporting the inner ends of said axle, and means arranged to be operated from the platform of said car for simultaneously moving the housings at either end of said car in opposite directions, forward or back, and thereby turning the wheels at an angle and narrowing the gage thereof.

2. The combination, with a railway-car provided with supporting-wheels each mounted upon an independent axle, of pivoted boxes supporting the outer ends of said axles and permitting said axles to have a longitudinal movement in said boxes, longitudinally-movable housings supporting the inner ends of said axles, and means arranged to be operated from the platform of the car for moving the inner ends of said axle forward or back, for the purpose set forth.

3. The combination, in a railway-car, with the wheels 8 and the axles 10, of the pivoted boxes supporting the outer ends of said axles, the longitudinally-movable housings supporting the inner ends of said axles, the sheave 20, the cable 22, connected with said housings and passing around said sheave, and the chain 27, connected to the opposite ends of said housings and passing around a sprocket-wheel 24, substantially as described.

In testimony whereof I have hereunto set my hand this 29th day of February, 1888.

WILLIAM H. JACOBY.

In presence of—

A. C. PAUL.

T. D. MERWIN.
